UNITED STATES PATENT OFFICE.

ALFRED M. CHAFFEE, OF OXFORD, MASSACHUSETTS.

MEANS FOR DELIVERING MOISTENED OR GLUE-COATED PAPER AND SIMILAR FABRICS.

1,138,538.

Specification of Letters Patent. Patented May 4, 1915.

Application filed May 15, 1914. Serial No. 838,812.

To all whom it may concern:

Be it known that I, ALFRED M. CHAFFEE, a citizen of the United States, residing at Oxford, in the county of Worcester and State of Massachusetts, have invented certain new and useful Improvements in Means for Delivering Moistened or Glue-Coated Paper and Similar Fabrics, of which the following is a specification.

- 10 My present invention relates to an improvement in mechanism adapted for facilitating the manipulation and delivery, from a continuous web, as desired, of a covering paper or fabric in moist, glue-coated, humidified, or more or less damp, pliable, weak, or flimsy condition; a prime object being to provide a simple and efficient means for the automatic feeding or delivery of moist glue-coated paper or similar fabric, in 15 broad webs, and controlled for starting the feed by giving a slight pull or draft upon the end of the paper itself, as required, and for stopping the feed-delivery by merely relinquishing the pull or hold upon the paper; 20 thereby relieving the attendant from the exertion and labor that might otherwise be necessary for advancing the moistened glue-coated fabric, and also relieving the moistened and weakened paper from excessive 25 strain and from liability of becoming wrinkled or torn as it is brought forward over the covering table or place of use.

Another object of my invention is to provide, in combination with the feeding or delivering means, of an efficient and convenient organization of means for the moistening or humidifying of a web of paper as it passes to said feeding or delivering means, and for regulating the humidifying action, 30 as more fully hereinafter explained.

Another object is to provide a roller feed delivery device pivotally fulcrumed for rocking action, and a frictional driving means therefor that is put into and out of 35 action by shifting the position of the rockable members upon their fulcrum axes. Also, to afford a construction of the roller supporting means that will permit ready 40 release and re-assembling of the individual 45 rolls.

I attain these objects by a mechanism, the nature and operation of which is illustrated in the drawings, wherein—

Figure 1 represents a part side part sectional elevation of mechanism embodying

my invention. Fig. 2 represents a front view of the set of feed-delivery rolls. Fig. 3 is an end view of the same. Fig. 4 is a section view at line X X on Fig. 2, and Fig. 5 is a longitudinal sectional detail showing means for the demountable support of the rolls.

Referring to the drawings, A indicates the main supporting frame; B an assembling or covering table to which the fabric or moist glue-coated paper is delivered for receiving such members as are to be inclosed therein, and C indicates a cutting-off shear for severing sheets from the end of the web of paper.

My improved feed-delivery mechanism comprises a pair or plurality of rolls 2 and 3 arranged parallel with each other and made of sufficient length to extend across the web of paper 4, which may be of any required width, more or less. Said rolls are disposed adjacent to each other, but preferably not in contact, and are mounted in a limitedly oscillatable frame or carrier, composed of end housings or bearing-members 5 that are supported upon the main frame, or brackets fixed thereon by pivots 7 or fulcrum joints located at position eccentric to and preferably at a short distance rearward from the axis of the primary or lower roll 2, the fulcrum axes being parallel therewith and in line with each other, so that the carrier or housings 5, together with the rolls mounted therein, can have a limited upward and backward swinging movement upon said fulcrum pivots. The rolls 2 and 3 may be journaled in bearings in the housings, or may be supported therein in a manner for ready detachment and re-assembling, as hereinafter more fully described. The housings at the opposite ends are rigidly connected together by rods or cross-bars 6.

The rolls are intergeared or connected to rotate in unison, by intermeshing spur-gears 8 upon their axles or equivalent means arranged within or adjacent to one of the housings. The under roll 2 is provided with a frictional faced wheel 9 fixed on its axle, and a counter-matching friction-wheel 10 is mounted upon a stud or arbor suitably supported upon the frame. The latter friction wheel is provided with a pulley 12 for a driving belt 13, whereby said frictional wheel 10 is operated. The friction-wheels 9 and 10 are located in such relation that the

frictional surfaces contact when the carrier or housings and rolls are oscillated forward or depressed, (see Fig. 3) but are relieved or out of contact when said carrier and rolls are oscillated backward in a slight degree. (See Fig. 4.) A stop device 14 is provided for limiting the backward swing and suitable adjusting means is provided for regulating the amount of clearance space between the friction surfaces when retracted.

10 A spring 15 or equivalent means is provided for affording a backward pull or preponderance for swinging the carrier or housing frame to its rearward position of oscillation for throwing the friction wheels 9 and 10 normally out of contact.

Fig. 5 shows the construction of the roll mounting devices when it is desired that the rolls be readily removable and replaceable 20 to facilitate cleaning. The rolls are made of thin metal tubes with heads, one of the heads is fitted with a socket 16 or means for interlockingly engaging with the axle on which the gears 8 are fixed, while the other head 25 of the roll is provided with a hollow bushing 17, and a screw stud 18 is threaded through the housing 5 and has a cylindrical end that is inserted within said bushing, and upon which the roll turns. A check-nut 30 19 is arranged upon the stud to screw up against the side of the housing for retaining the adjustment.

By turning back the screw stud its end is withdrawn from the bushing and the roll 35 can then be taken out of the carrier, its opposite end being freed by a mere endwise movement. It can as readily be replaced by a reversal of this operation.

20 indicates an upright inclosed box or 40 chamber wherein the paper acquires moisture, and from which the web passes beneath the guide roll 21 to the delivery roll 2. In the lower part of said chamber there is an oblong open-topped trough or pan 22 45 having a steam-pipe therein, and adapted for containing water which is heated and evaporated by the steam pipes, making a rising vapor for moistening the paper as it passes through the chamber. Above the pan 50 22 is a carrier-roll 23 mounted in bearings 24 which are preferably adjustable up and down on their supports for varying the amount of paper surface exposed to the vapor at one time, and thus regulating 55 the degree of dampness imparted to the paper.

25 indicates means for applying glue to one surface of the paper, comprising a glue-reservoir provided with a delivering roll 26 60 over which the paper is passed, and having suitable guide bars for directing the web in contact with the glue-delivering roll.

44 indicates the roll of paper or fabric from which the web 4 is supplied. Said roll 65 of paper may be supported by any suitable

means at a convenient location. The apparatus may be constructed to accommodate a web of paper or fabric of any desired width; ordinarily widths of from two to four feet, more or less, are employed. The web 4, as 70 herein illustrated, passes from the roll 44, over the glue-roll 26 and beneath the guide-roll and up to and over the carrier-roll 23 within the moistening chamber 20, where it becomes humidified and rendered more or 75 less soft and weakened; thence under the guide 21 to the primary feed-delivering roll 2, thence upward at the front of said roll and rearward beneath and forward over the delivering-roll 3 to the cutting-off shear C 80 or place of use B.

In the operation of my improved feed-delivery mechanism, the attendant reaches across the shear line and takes hold of the end of the moist paper near the corners, and 85 gently pulls it toward the front. This slight pull swings forward the carrier and feed-roll mechanism upon the housing fulcrum pivots 7, causing the friction-wheel 9 to come into engaging contact with the 90 power driven friction-wheel 10, thereby immediately imparting forwardly rotative movement to the rolls 2 and 3, which then automatically reel off the web 4 in a uniformly smooth, regular, and easy manner so 95 long as the attendant carries forward the free outer end of it; thus requiring only such action by the attendant as will keep the delivered portion of the paper taut to a degree sufficient to counterbalance or 100 maintain the preponderance of the oscillating carrier or roll-housing frame at forward position; the driving power doing all the work of pulling the web from the roll 44, passing it over the glue-roll 26, through the 105 damping process, and about the several intermediate rolls or guides. When the end of the paper has reached the predetermined mark or position above the table the attendant merely stops the forward movement of his hands, and the automatic delivery of the web immediately ceases, by reason of the normal backward swing of the housing frame and feed-rolls taking the friction members 9 and 10 out of contact as 110 the preponderant force exerts itself at the rearward side of the fulcrum axis. When the paper is delivered over the table to the required length, the attendant brings the shear C into action and severs the sheet from 115 the web, leaving the newly severed end of the web in condition for repeating the operation. The shear is operated by the rod 28, lever 30, and cam 31 on shaft 32; the pulley 33 being combined with the cam-shaft by an automatic stop clutch 34 that is let into action by connections having a controller detent 35 located to be moved by the hand of the operator as the web is 120 drawn to the desired limit.

I claim as my invention and desire to secure by Letters Patent—

1. A mechanism for the purpose described, comprising a pair of rolls, a rockable housing frame in which said rolls are mounted, fulcrum pivots for said housings disposed at positions eccentric to the axis of the primary roll, a friction wheel fixed on the axle of said primary roll, a drive-friction wheel or pinion mounted adjacent to said friction wheel, but normally out of contact therewith, means for operating said drive-friction wheel, means for counterbalancing or returning said housing-frame to its primary position, a limiting stop for arresting the swing movement of the housing frame and suitable gearing operatively connecting the axles of said rolls.

2. In a mechanism for the purpose described, in combination, a pair of web-carrying-rolls, means connecting the pair for simultaneous rotation, housings in which said rolls are mounted, said housings being pivotally fulcrumed at a position rearward from the roll axes, a friction wheel secured upon the axle of one of said rolls, a driving element provided with a friction wheel against which said first named friction-wheel is brought into contact by forward swing and relieved from contact by backward swing of said housings, means for normally retracting said housings and rolls, said retracting means adapted to be overcome, and the friction members put into active contact by a slight forward pull upon the paper or fabric about said rolls.

3. A web delivering mechanism for the purpose specified, comprising a plurality of non-contacting rolls inter-gearred for rotating in unison; a pivotally fulcrumed oscillatable bearing supporter on which said rolls are mounted, means for limited backward preponderance to said supporter, a frictional driving means for operating said rolls, the frictional engaging faces of which are relatively disposed to be out of engagement when said supporter is at its backward position, and to be brought into operative engagement by the forward oscillation of said supporter, substantially as set forth.

4. The combination with means for glue-coating and means for moistening paper in a continuous web; of a feed-delivery means comprising a plurality of web-carrying rolls about which the paper passes, a rockable support for said rolls, means for the automatic operation of said rolls for advancing the paper or web, a counter-poising means for normally retaining the same out of action, said mechanism adapted to be temporarily thrown into operative automatic feeding action by a slight forward pull or

draft applied to the advance end of the web, and to assume non-active relation when such pull or draft is relinquished.

5. In a mechanism for the feed-delivery of damp paper or the like, the combination with means for moistening a web of paper, a carrier-roll for supporting the web, an exit-guide roll, a feed-delivery means comprising a plurality of intermeshingly geared web-carrying rolls mounted on a rockable frame supported on fulcrum pivots eccentric to the roll axes, a mechanical actuating means for rotating said rolls, said actuating means brought into action by rocking forward the roll-supporting frame by a pull upon the end of the delivered web.

6. In a mechanism for the feed-delivery of damp paper or the like, the combination with means for moistening a web of paper, guide rolls for directing the web, a feed-delivery means comprising two intermeshingly geared web-carrying rolls mounted on a rockable frame supported on fulcrum pivots in rear of the roll axes, a mechanical actuating means for rotating said rolls, said actuating means brought into action by rocking forward the roll-supporting frame by a pull upon the end of the delivered web, an automatic cutting off shear for severing a predetermined part of the delivered web, actuating mechanism for said shear, a stop clutch therefor and a clutch-tripping connection having its controlling member disposed approximately at the position to which the end of the web is drawn.

7. In a mechanism of the character described, in combination, a rockable carrier comprising two roll-supporting housings rigidly connected to each other laterally by cross bars, and having fulcrum pivoting means parallel with but offset from the roll axes; one of said housings having axle members mounted to rotate therewith, with intermeshing gears fixed on said axle members within the housing, and a friction wheel upon one of said axle-members; a friction drive member for actuating said friction wheel, a pair of screw-threaded studs having cylindrical inner ends arranged through the other housing, the removable rolls having heads or ends that are respectively fitted for inter-engagement with the gear-axle-members, and for receiving the cylindrical end of said screw-stud, and means for effecting and for retaining adjustment of said screw-studs.

Witness my hand this fourth day of May 1914.
